LIFEBOAT LAUNCHING DEVICE

Thomas Niblett, Carvel Beach, Md.

Application August 28, 1939, Serial No. 292,328

9 Claims. (Cl. 9—22)

This invention relates to a launching device for launching boats from ships, the general object of the invention being to provide means whereby the boat can be easily and quickly swung over the side of a ship and then lowered and released from the supporting means and in the minimum amount of time and with the least manual effort and without the use of blocks and falls, etc.

Another object of the invention is to provide a flexible screw shaft with a rotary nut member for moving the shaft longitudinally, for performing certain movements of the launching action, with hollow members for enclosing parts of the screw shaft to protect the same from the elements. Another object of the invention is to provide a hollow davit for supporting the nut member and the motor rotating the same and for receiving portions of the screw shaft, with means for moving the davit inwardly and outwardly, said means including flexible screw shafts and rotary nut members.

Another object of the invention is to provide means whereby the flexible screw shaft used for lowering and raising a boat can be easily and quickly attached to or detached from parts of the boat, said means being of such a nature that they will not interfere with the occupants of the boat and will take up but little room in the boat when the boat is detached from the screw shaft. This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which: Figure 1 is a diagrammatic view partly in elevation and partly in section showing the invention in use for launching a boat from a ship.

Figure 2 is a plan view of a lifeboat constructed in accordance with the invention.

Figure 3 is a longitudinal sectional view through the boat shown in Figure 2.

Figure 4 is a vertical sectional view through the nut member, the motor for driving the same and the casing carried by a davit and this view also showing portions of the flexible screw shaft with parts thereof broken away and with end portions in section.

Figure 5 is a fragmentary top plan view of a seat or thwart of the life boat with the means

for coupling a flexible screw shaft thereto, the cover of such means being in open position.

Figure 6 is a transverse sectional view through the lifeboat and the coupling means with the cover in closed position and the coupling means in inoperative position.

Figure 7 is a view similar to Figure 6 but showing the coupling means engaged by the lower end of a flexible screw shaft so that the life boat is connected with the screw shaft.

Figure 8 is an elevation of the lower part of a screw shaft.

Figure 9 is a bottom plan view of the lower end of the female coupling member at the lower end of the screw shaft.

Figure 10 is a view in elevation with parts broken away of the sliding sleeve forming part of the coupling means of the lifeboat.

Figure 11 is a top plan view with parts in section of the means for moving the davit on the curved supporting members.

Figure 12 is a section on the line 12—12 of Figure 11.

Figure 13 is a view on the line 13—13 of Figure 11.

Figure 14 is a transverse view through Figure 11.

In these views the letter A indicates a part of a ship and the letter B the lifeboat of the ship and in carrying out the invention several davits 1 are provided for each lifeboat, each davit being of hollow construction as shown and having a bell mouth 2 at its upper end with its lower end pivoted to a bracket 3 attached to a part of the deck. Said bracket including a tubular part passing through the deck and to which a tube 4 may be connected for guiding the slack of the flexible screw shaft 5 when said shaft has a portion depending from the lower or inner end of the davit. Said shaft 5 is formed of a wire core 5' made up of a plurality of strands of wire to form a wire rope or cable, and a bar 5" of steel wound around the core and suitably connected therewith, this bar or rod 5" being preferably a wire drawn rod of a shape to form a thread of the desired configuration, the drawings showing this thread as a "butress thread." Also, as shown in Figure 4, the rod is wound around the core in an opposite direction from that in which the strands are wound in producing the core.

A casing 6 is provided with the trunnions 7 which engage bearings in the bell mouth of the davit so that the casing is suspended from the davit and has its upper cover part 6' located in said bell mouth. Said cover part 6' is formed with an opening 8 for the passage of the flexible

shaft 5 and the lower end of the casing turns upwardly and inwardly to form an opening 9 for the passage of the shaft. A nut member 10 is rotatably arranged in the casing and anti-friction bearing means 11 are located between the lower end of the nut member 10 and the upwardly curved part of the bottom of the casing, as shown in Figure 4. A plate-like member 12 is seated on a ledge 13 in the top of the casing and the nut member passes through a centrally arranged hole in the member 12 and has its upper end provided with an enlargement 14 and antifriction means 15 are located between this enlarged part 14 of the nut member and the member 12. Thus the nut member is rotatably arranged in the casing and is supported by antifriction bearing means. An electric motor is located in the casing for rotating the nut member and said motor is indicated generally at M and includes the armature 16 suitably connected with the nut member, the fields 17 and the brush means 18, the wires leading to the motor from a suitable source of supply being indicated at 19 in Figure 1.

The nut member may be formed in sections 25 and preferably the lower section is formed with a spiral passage therein for engaging a part of the spirally threaded shaft 5, as shown in Figure 4 with the rest of the nut member having an enlarged spiral passage therein, this passage being 30 so much larger than the thread of the shaft 5 that said thread could pass through the passage of the nut member if it were not for the lower reduced part of the passage. Roller bearings 20 are placed between the walls of the spiral passage 35 of the nut member and the threads of the shaft 5 and ball bearings 21 are associated with the roller bearings, the ball bearings engaging the ends of the roller bearings and both sets of bearings being held in place by a suitably formed 40 retainer 22. A filler member 23 is placed in the top of the passage of the nut member and a retainer plate 24 is fastened by bolts to the top of the nut member for holding the filler member 23 in place and also holding lubricant in place which 45 has been pressed between the bearings and the walls of the passage and the threads of the shaft 5.

Thus it will be seen that the anti-friction bearing provided by the rollers and balls will reduce 50 friction to the minimum and the rotary movement of the nut member will move the shaft 5 longitudinally through means of such antifriction means and thus the shaft 5 can be raised or lowered in accordance with the direction of rotation 55 of the motor. It will be understood that as the shaft 5 is being raised by the nut member that part of the shaft passing from the top of the casing will move along the curved part of the davit and then downwardly through the davit and 60 if the slack part of the shaft is of greater length than the length of the davit then the shaft will finally pass through the bracket 3 and into the tube 4.

Thus only the part of the shaft which depends 65 from the nut member or casing 6 is exposed to the elements as the rest of the shaft is enclosed in the davit and the member 4 and there are no parts of the shaft to be in the way of passengers or crew.

70 The outer circumference of the enlarged part 14 of the nut member forms a brake drum for a brake band 26 which is supported from the member 12 as shown at 27 in Figure 4 and the ears 28 of the band are provided with threaded 75 holes engaged by left and right threaded parts on

a shaft 29 which has an arm 30 attached thereto to which a flexible member 31 is connected, this flexible member passing through an opening in the cover part 6' and through a table 32 to an operating lever 33 so that by properly rotating the shaft 29 the band can be expanded or contracted and when contracted will hold the nut member against rotary movement, after the motor has been stopped, thus holding the screw shaft 5 against downward movement under the weight 10 of a boat attached to its lower end.

Each end of the shaft 5 has a part of the thread forming member 5' cut therefrom and then the strands of the core 5' are passed through perforations in a disk 35, the perforations preferably being inclined to the axis of the disk and the ends of the wires passing through the perforations are knotted to prevent the ends from being pulled through the perforations. A pair of gripping jaws 36 is associated with each disk 20 35 and these jaws are formed with internal parts which conform to the spiral thread of the shaft 5 so as to engage portions of this thread and then a coupling member 37 is placed over the lower or outboard end of the shaft and a sleeve 38 over 25 the other or inboard end of the shaft, the parts 35' and 36' in the sleeve 38 being similar to the parts 35 and 36 in the sleeve 37. The disk and gripping members with the internal parts of the sleeve at each end of the shaft are preferably 30 formed with interrupted threads for interlocking with each other in the manner set forth in my Patent Number 2,115,743, dated May 3, 1938. The inboard end fixture has a pipe section 39 in the sleeve 38 which abuts the disk 35' and a bolt 40 35 passes through the sleeve and this pipe section, as shown in Figure 4. If desired rollers can be placed on the ends of this bolt 40 to engage portions of the davit which should be formed as track parts for receiving such rollers.

The exterior shape of the sleeve 37, which forms a coupling for connecting the shaft to the boat B is preferably of the shape shown in Figures 8 and 9 which shows the sleeve having a flat part 37' and a wedge part 37" at opposite side 45 portions and the lower end of this sleeve 37 has its bore formed with interrupted or mutilated threads 41 as shown in Figures 4 and 9.

The boat B is provided with means for receiving the coupling members 37 at the lower ends 50 of the threaded shafts and as the drawings show the boat adapted to be launched by two davits the boat is provided with a pair of the coupling members. As shown each set of members includes a standard 42 connected with the bottom 55 of the boat and extending upwardly into a hole in a seat or thwart 43 of the boat. A tubular member 44 is rotatably arranged in said opening in the seat or thwart and is held in place by a collar 45 threaded to the upper end of the tubular part and the lower end of the tubular part has connected therewith the handle forming parts 46. This tubular part with its handle parts forms a wrench. A sleeve 47 having its bottom closed and with an inwardly extending flange 48 at its top, 60 is slidably arranged on the shaft 42 but is held against rotary movement thereon by means of a key 49 on the shaft engaging a keyway in the bottom of the sleeve. A disk 50 is fastened to an intermediate part of the shaft 42 and is located in the sleeve and forms a seat for the lower end of a coiled spring 51 encircling the shaft and located in the sleeve with the upper end of the spring bearing against the flange 48. The upper 65 part of the shaft 42 is enlarged and forms a male 70 part of the shaft 42 and is located in the sleeve and forms a seat for the lower end of a coiled spring 51 encircling the shaft and located in the sleeve with the upper end of the spring bearing against the flange 48. The upper 75 part of the shaft 42 is enlarged and forms a male

member which is provided with the mutilated threads 53 and the spaced enlargements 54 on its bottom. These enlargements being engaged by the flange 48 of the sleeve when the sleeve is in lowered position as shown in Figure 7. A hinged cover 55 is provided for closing the upper end of the tubular part 44 of the wrench when desired so as to prevent foreign matter from getting into the interior of the sleeve and on the parts there-
 5 in. The exterior of the sleeve is formed with a bayonet groove 56, see Figure 10, the upper horizontal part of which terminates in a hole 57. A spring actuated latch bar 58 is carried by one of the arms of the wrench, the spring acting to hold
 10 the inner end of the latch bar in the groove 56 and to project it into the hole 57 when the hole comes opposite the latch, this hole 57 being formed in the flange carrying part of the sleeve. A flexible member 59 is connected with the latch
 15 bar and passes over suitable guiding pulleys 60 in the boat to a block and tackle 61 located at the rear of the boat so that the coxswain can manipulate the block and tackle, or a lever, connected with the cables or flexible members 59 to
 20 actuate both of the wrenches and the latch bars 58.

The interior formation of the parts 44 of each wrench is made similar to the exterior shape of the member 37 at the lower end of the flexible
 25 shaft 5 so that this part 37 can be placed in the tubular part of the wrench and then when the wrench is turned by a pull upon the flexible member 59 the part 37 will be rotated with the tubular part of the wrench. As the part 37 is pushed into the tubular part of the wrench it will force the sleeve 47 downwardly which will compress the spring 51 and the spaces between the mutilated threads 41 in the member 37 will pass through the grooves formed by the mutilated
 30 threads 53 of the shaft 42 and then when the member 37 is turned by turning movement of the wrench the threads 41 of member 37 will interlock with the threads 53 of the standard or shaft 42 and thus the shaft 5 will be firmly locked to the coupling means of the boat. As the sleeve 47 moves downwardly the latch pin will at its inner end pass up the groove 56 and then when the wrench is turned to lock the female member 37 with the male member or standard 42 the pin
 35 will move through the horizontal part of the groove 56 until it reaches the end of the groove and then its spring will project it into the hole 57 in the sleeve and this locks the parts with the mutilated threads of the member 37 inter-engag-
 40 ing with the mutilated threads 53 of the member 42.

It will be understood that the engagement of the members 37 of the shafts 5 with the coupling members of the boat B is done by hand and the wrenches are turned by hand with the operator sitting close to the parts. However, when the boat is to be released from the shafts 5 then the coxswain can exert a pull upon the flexible members 59 which releases the latch bars 58 and at the same time rotates the wrenches so that the mutilated threads of the members 37 and 42 are disengaged and the sleeves 47 released from the latch pins so that the springs 51 in the sleeves will force the sleeves upwardly and cause said sleeves to push the members 37 from out of the wrenches and thus the boat will be free of the shafts 5. Of course, if the boat is released from the members 37 while it is suspended in midair then gravity or the dropping of the boat will free the members 37 from the wrenches after the

wrenches have been moved to releasing position.

Each davit can be swung inwardly and outwardly as shown in full and dotted lines in Figure 1 and during this movement wheels 70 carried by the davits engage the arcuate track forming members 71 supported from the ship's deck, one on each side of a davit and these track members are of hollow construction as shown. Each carriage includes a two part tubular clamp 72 for clamping around an intermediate part of the davit and the shafts 73 for the wheels 70 extend from opposite sides of the clamp. Shanks 74 also extend from opposite sides of the clamp and below the shafts 73 and these shanks carry the gripping means shown generally at 75 which are located in the track members, the shanks passing through slots 76 in the inner sides of the track members and these slots communicate with the bores 77 of the track members. These clamping means 75 engage the ends of flexible threaded shafts 78 which pass through the bores 77 of the track members 71 and these clamping members 75 are made somewhat similar to those which hold the members 37 and 38 to the ends of the shaft 5. As shown each clamping part 75 includes a disk 79 having holes therein for receiving the wires of the core 78' of the shaft 78 with the sectional members 80 somewhat similar to the members 36 engaging the disk 79 and pins 81 passing through these members 80 and through the thread forming bar 78" of the shaft 78 and the threads of said members 80. Thus the flexible threaded shafts 78 are connected with the clamp member 72 so that the member 72 with the davit is moved along the track members as the threaded shafts 78 are moved in one direction or the other by the rotary nut members 82 rotatably supported in a housing 83 supported by a supporting structure 84 from the deck of the ship as shown in Figure 1. A motor M' has a pinion 85 on its shaft which meshes with the gears 86 connected with the nut members so that the two nut members are rotated from the motor to impart simultaneous movement to the two screw shafts 78 which, in turn, impart movement to the clamps 72 and the wheels 70 which move the davit inwardly or outwardly. Each nut member 82 is formed with the internal spiral threads in which are located the rollers 87 which also enter the threads of the shaft 78 which are formed by the bars 78" suitably attached to the wire core 78'. It will be seen that this flexible threaded shaft 78 is similar to that shown at 5 excepting that the threads are of square formation instead of the tapered formation shown in Figure 1. The rollers 87 are carried by a retainer 88 and anti-friction bearings 89 are located between the ends of the nut member 82 and the adjacent parts of the housing. Plates 90 are fastened to the ends of the nut member and have their inner circumferences shaped to engage the threads of the shaft 78 as shown in Figure 13.

Suitable switch means 91 are provided for controlling the current to the reversible motors M' and the inner ends of the track members 71 are extended downwardly through the deck as shown at 71' in Figure 1 so that the flexible shafts 78 will pass downwardly through these parts 71' as the davit is being moved inwardly to the dotted line position shown in Figure 1.

If it is not desired to use the motor construction shown in Figure 4 then the nut member shown in this figure can be driven by gearing from a motor, somewhat similar to the arrangement shown in Figure 11.

The control for the motors M' for moving the two davits and the motors M for actuating the nut members which control the movement of the shafts 5 should be such that they can be actuated by a single operator so that the boat when being launched will be moved on an even keel and the coxswain by manipulating the cables 59 can release both ends of the boat from the shafts 5 simultaneously. Of course, in launching the boat after the boat has been connected with the ends of the shafts 5 the davits are swung outwardly of the dotted line position to the full line position shown in Figure 1 and then the motors M are actuated to lower the shafts 5 and then the coxswain manipulates the flexible members 59 to release the boat from the lower ends of the shafts 5 . Of course, in raising a boat the operation is reversed, the boat being connected to the lower ends of the shafts 5 and then the motors M are started so as to cause the shafts 5 to raise the boat and then the davits are swung inwardly and the boat placed on a suitable chock or cradle. By using the flexible shafts and having them enter hollow davits and hollow track members there are no loose ends or cables or the like for getting in the way of persons on the ship or boat or injuring persons and the parts are enclosed to protect them from the elements.

The female member 37 and the male member 30 or upper part of the shaft 42 can have their thread arrangement formed similar to the before-mentioned patent.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A boat launching device comprising a davit pivotally supported at its lower end, means for swinging the davit inwardly and outwardly, a flexible screw shaft passing through the davit and extending from the outer end thereof, a nut member, a housing for the same pivotally supported from the outer end of the davit, means for rotatably supporting the nut member in the housing, the screw shaft passing through the nut member and means for rotating the nut member to impart longitudinal movement to the screw shaft.

2. In a boat launching device, a hollow davit having a mouth, a housing depending from the mouth and pivotally supported therein, a nut member rotatably arranged in the housing, a flexible screw shaft having a part passing through the davit and a part passing through the nut member, means for rotating the nut to impart longitudinal movement to the flexible screw shaft and anti-friction means between the nut member and the screw shaft.

3. In a boat launching device, a hollow davit having a bell mouth, a housing depending from the bell mouth and pivotally supported therein, a nut member rotatably arranged in the housing, a flexible screw shaft having a part passing through the davit and a part passing through the nut member, means for rotating the nut to impart longitudinal movement to the flexible screw shaft and anti-friction means between the nut member and the screw shaft, said anti-friction means including roller and ball bearings.

4. In a boat launching device, a hollow davit having a bell mouth, a housing depending from the bell mouth and pivotally supported therein, a nut member rotatably arranged in the housing, a flexible screw shaft having a part passing through the nut member, means for rotating the nut to impart longitudinal movement to the flexible screw shaft and anti-friction means between the nut member and the screw shaft, said anti-friction means including roller and ball bearings, said screw shaft including a core formed of strands of wire wound together and a thread forming bar wound around the core to form the thread.

5. In a boat launching device, a davit of hollow construction, a housing depending from the mouth of the davit and pivotally supported therein for rocking movement, a nut member rotatably arranged in the housing, means for rotating the nut member, a flexible screw shaft passing through the davit and through the nut member and moved longitudinally by rotary movement of the nut member and means for detachably connecting the lower end of the screw shaft to a boat.

6. In a boat launching device, a davit of hollow construction, a housing depending from the mouth of the davit and pivotally supported therein for rocking movement, a nut member rotatably arranged in the housing, means for rotating the nut member, a flexible screw shaft passing through the davit and through the nut member and moved longitudinally by rotary movement of the nut member and means for detachably connecting the lower end of the screw shaft to a boat, said means including a male member in the boat having mutilated threads, a female member on the lower end of the screw shaft having interrupted or mutilated threads, wrench means in the boat for receiving the female member and rotating the same to interlock the mutilated threads of the female member with the male member.

7. In a boat launching device, a davit of hollow construction, a housing depending from the mouth of the davit and pivotally supported therein for rocking movement, a nut member rotatably arranged in the housing, means for rotating the nut member, a flexible screw shaft passing through the davit and through the nut member and moved longitudinally by rotary movement of the nut member and means for detachably connecting the lower end of the screw shaft to a boat, said means including a male member in the boat having mutilated threads, a female member on the lower end of the screw shaft having interrupted or mutilated threads, wrench means in the boat for receiving the female member and rotating the same to interlock the mutilated threads of the female member with the male member, a spring-pressed sleeve surrounding the male member and means for locking the sleeve in position, when the female member is in engagement with the male member for preventing movement of the wrench.

8. In boat launching means, a davit pivotally supported at its lower end, said davit being of hollow construction, a housing supported for rocking movement in the mouth of the davit, a nut member in the housing, means for rotating the nut member, a flexible screw shaft passing through the davit and through the nut member, means for connecting the lower end of the shaft to a boat, a curved track for the davit of hollow construction, a carriage attached to the davit

and engaging the track, flexible screw shafts passing through hollow portions of the track and connected with the carriage, stationary supporting means, nut members supported thereby and 5 encircling the last-mentioned flexible screw shafts, a motor for driving the last-mentioned nut means.

9. In boat launching means, a davit pivotally supported at its lower end, said davit being of 10 hollow construction, a housing supported for rocking movement in the mouth of the davit, a nut member in the housing, means for rotating the nut member, a flexible screw shaft passing through the davit and through the nut member,

means for connecting the lower end of the shaft to a boat, a curved track for the davit of hollow construction, a carriage attached to the davit and engaging the track, flexible screw shafts passing through hollow portions of the track and connected with the carriage, stationary supporting means, nut members supported thereby and encircling the last-mentioned flexible screw shafts, a motor for driving the last-mentioned nut means, each last-mentioned nut means including a member having a spiral thread therein, rollers located in said thread and engaging the thread of the flexible shafts. 10

THOMAS NIBLETT.
